UNITED STATES PATENT OFFICE.

FREDRICK C. DAMM, OF CLEVELAND, OHIO, ASSIGNOR TO THE CLEVELAND TARGET COMPANY, OF SAME PLACE.

TARGET-TRAP.

SPECIFICATION forming part of Letters Patent No. 374,043, dated November 29, 1887.

Application filed April 28, 1887. Serial No. 236,507. (No model.)

To all whom it may concern:

Be it known that I, FREDRICK C. DAMM, a citizen of the United States, residing at Cleveland, in the county of Cuyahoga, State of 5 Ohio, have invented certain new and useful Improvements in Target- Traps; and I do hereby declare that the following is a clear, full, and exact description of the invention, which will enable others skilled in the art to 10 which it appertains to make and use the same.

This invention relates more particularly to improvements in carriers for target-traps, and in which, prior to this invention, such carriers have been provided with opposing jaws, 15 one of which was spring-actuated, and between which the target was held in the act of being thrown from the trap in such manner as to give a rotary motion to the target during its flight, in which it is assisted by a stationary 20 or revolving pin, against which the target is held during the throwing operation. In such prior construction, however, the spring-jaws tend to exert a crushing force upon the targets to such an extent as to often fracture the 25 targets in the act of throwing the same, the grip of said jaws being necessarily very great because of the insecure position in which the target is held between the two diverging jaws of the carrier, one jaw of which, although 30 bifurcated, simply serving to prevent a vertical displacement of the target, and in nowise tending to reduce the power of the necessary grip of the opposing jaws upon the target.

Another objection to carriers as heretofore 35 constructed is that the bifurcated jaw for reception of the target has had its arms substantially rigid with relation to each other, so that targets having rims of varying heights could not be secured in position by these arms except by their lateral gripping force alone, and targets having rims of widely-differing heights 40 cannot be placed in position at all.

The prime object of this invention is to so 45 construct the carrier that while one of the jaws exerts a yielding pressure or gripping force upon the target the grip is directed in such manner that it has no tendency whatever to fracture the target.

Another object is to have such a jaw adapted to receive and hold securely in place targets 50 varying in dimensions both as regards diameter and height of rim.

Other objects are to have the yielding jaw exert a gripping force upon the rim only of the target and at all times, but which jaw shall be 55 so pivoted with relation to the target as to release the target upon the slightest movement thereof away from the target; to provide a stationary or revolving pin corrugated on its periphery so as to engage a corresponding corrugation in the periphery of a target-rim, 60 whereby an axial rotation is imparted to the target in its flight, and to provide certain details of construction in carrying out my invention, all as illustrated in the accompanying 65 drawings, in which—

Figure 1 represents a plan view of a carrier embodying my invention; Fig. 2, a side elevation thereof, showing the target in dotted lines; and Fig. 3, a sectional view on line X X of 70 Fig. 1, looking in the direction indicated by the arrows.

Similar letters of reference indicate the same parts in the several figures of the drawings.

Referring by letter to the accompanying 75 drawings, A indicates the outer end of the throwing-arm of a target-trap, which may be actuated in any common and well-known manner usual in this class of devices, to the end of which arm is pivotally secured the target-carrier, consisting of a base-plate or target-support, B, the free end of which is bifurcated so as to form two arms, C D, extending outwardly for the main portion, and diverging sufficiently to form a rest for the target, the 80 spread of the arms, however, being preferably sufficient to accommodate targets of the largest size. To the outer end of the arm C is secured an upright pin or stud, E, corrugated on its periphery and forming one bearing-point for the target when in position on the carrier, against which presses the periphery of the rim of the target, also corrugated, as shown, a second bearing-point for which is formed by another projection of stud F at the 85 point of conjunction between the arms C and 90

D, the projection in the construction shown being simply an upturned lip from the base B, which is composed in this case of sheet metal. This feature, however, is unimportant, 5 and may vary according to the desire of the manufacturer. The studs E and F are so placed with relation to each other that a target of the smallest diameter cannot be passed between them, thus forming two bearing-points 10 upon the rim of the target, against which the target is pressed by the yielding jaw, now to be described, lying above the arm D of the base-plate. This yielding jaw G, as shown, extends approximately parallel with the arm 15 D, but lies at an oblique angle thereto, as will more clearly be seen by reference to Fig. 3, in which the said jaw is shown as pivoted at its rear end to an angular projection, H, bent up from or otherwise rigidly attached to the base-plate of the carrier. The free end of this jaw, 20 extending forward of the pivot, is unsecured and totally disconnected from the base-plate, and being composed of spring metal, by reason of its nature constitutes a yielding-jaw or 25 gripper; but in order to enlarge the capacity of the carrier, so as to operate in connection with targets of extreme dimensions, I prefer to render said jaw still more yielding by subjecting the same to an independent spring- 30 tension, which is accomplished by giving said jaw an extension, I, at substantially right angles to the gripping end thereof, the outer end of which extension is engaged by a swivel-bolt, J, working freely through an up- 35 right stud or post, K, secured to the base-plate. Upon this bolt is sleeved a coil-spring, M, confined between the stud K and an adjustable nut, L, working upon the outer end of the bolt J, the tension of which spring actuates the bolt, and consequently the angular end I of the jaw, in such manner as to cause the free end of said jaw, by reason of its inclined position, to approach the target-support. Thus it will be seen that a target placed 40 upon the base-plate between the studs E and F will be gripped by the spring-jaw G upon the rim thereof with a downward pressure, so as to hold it in close contact with the base 45 until released by the throw of the carrier, the studs E and F serving merely as auxiliaries to prevent a lateral displacement of the target and to permit a lessening of the gripping force of the said spring-jaw. The gripping force of the spring-jaw, it will be observed, is exerted 55 entirely upon the thick rim of the target and not upon the thinner crown or center thereof, so that the liability of fracturing the target is reduced to a minimum; and it will also be observed that by reason of the inclined pivoting 60 of the spring-jaw the said jaw is enabled to accommodate targets having rims of widely-differing heights, but to grip them all with an equal and any desired force, the power of the grip being readily adjusted by the nut L and spring M, heretofore described, the inclined pivoting of the jaw also serving as an

auxiliary in releasing the target, it requiring only the slightest movement of the jaw to entirely release the target in such manner as to clear it. It is also apparent that the corrugations in the periphery of the targets, acting in conjunction with the corrugated pin or stud on the base-plate, produce an axial rotation of said target in its flight, the target by the centrifugal force employed in its discharge being 75 forced against and rolling upon or around the said pin or stud while its opposite side is released by the spring-jaw.

In conclusion, I may add that while it is preferable to have the gripper-jaw G composed 80 of spring metal, so as to be elastic or yielding independent of the spring-cushion M and the accompanying devices, it would be no departure from the spirit of my invention to have this jaw composed of inflexible material, because the said spring and adjustable devices would render said jaw sufficiently yielding to make the same operative.

Having described my invention, what I claim, and desire to secure by Letters Patent, 90 is—

1. In a target-trap, the throwing-arm and the target-support or base-plate thereof, in combination with a spring-actuated gripper-jaw, the line of strain of which is at an oblique angle to the plane of the target-support, substantially as described. 95
2. In a target-trap, the throwing-arm and the target-support thereof, in combination with a spring-actuated gripper-jaw pivoted to said support, the line of strain of which is at an oblique angle to the plane of the target-support, substantially as described. 100
3. In a target-trap, the throwing-arm, the target-support or base-plate thereof, a pivot-connection between said arm and support, and stops or studs projecting from said support, in combination with a spring-actuated gripper-jaw pivoted to said support, the axis of said pivot being oblique to the plane of the target-support, whereby said jaw moves toward and away from said support in an oblique line, substantially as described. 105
4. In a target-trap, the throwing-arm, a base-plate pivoted thereto, and stops or studs projecting from said base-plate, in combination with a gripper-jaw pivoted to said base-plate in an inclined position, and an adjustable spring-actuated bolt working loosely through a projection on the base-plate and engaging 115 said gripper, substantially as described.
5. In a target-trap, the throwing-arm, a base-plate pivoted thereto, and a corrugated stop or stud projecting from said base-plate, in combination with a flying target corrugated 125 upon the rim thereof for engaging said stop or stud, and an opposing spring-actuated gripper-jaw for retaining the target in position upon the base-plate, whereby an axial rotation is imparted to the target in its flight, substantially as described. 130
6. In a target-trap, the throwing-arm, a

base-plate pivoted thereto, and one or more stops or studs projecting from said base-plate, the outer end one of which is corrugated on its periphery, in combination with a flying target having a rim corrugated on its periphery for engaging said corrugated stud, and an adjustable spring-jaw pivoted to said base-

plate in an inclined or oblique position, substantially as and for the purpose set forth.

FREDRICK C. DAMM.
